UNITED STATES PATENT OFFICE.

HORACE T. CLARK, OF BRIDGEPORT, CONNECTICUT.

ELECTRIC SWITCH.

SPECIFICATION forming part of Letters Patent No. 451,268, dated April 28, 1891.

Application filed February 25, 1891. Serial No. 382,814. (No model.)

To all whom it may concern:

Be it known that I, HORACE T. CLARK, a citizen of the United States, residing at Bridgeport, in the county of Fairfield and State of Connecticut, have invented certain new and useful Improvements in Electric Switches; and I do hereby declare the following to be a full, clear, and exact description of the invention, such as will enable others skilled in the art to which it appertains to make and use the same.

My invention relates to certain new and useful improvements in electric switches, and has for its object to provide a device of this description, either single or double pole, of the variety known as the "snap-switch," which shall be simple in construction, and in which, as is usual in the better class of snap-switches, both the make and break movements shall be spring-actuated; and with these ends in view my invention consists and resides in the construction and combination of elements hereinafter fully explained, and then recited in the claims.

In order that those skilled in the art to which my invention appertains may fully understand its construction and method of operation, I will describe the same in detail, reference being had to the accompanying drawings, which form a part of this specification, and in which—

Figure 1 is a plan view of a double-pole switch embodying my invention; Fig. 2, a side elevation showing such a double-pole switch in its closed position; Fig. 3, a vertical section on the line $x-x$ of Fig. 1, the switch being closed; Fig. 4, a view similar to Fig. 3, but showing the switch open.

Like numerals denote the same parts in all the figures of the drawings.

1 is a base of any suitable material, preferably porcelain or wood. Upon this are mounted circuit-terminals 2, which may be of any approved form. Upon the center of the base 45 is a housing 3 open toward the terminals, as shown in the sectional figures. It is secured in place in any suitable manner—as, for instance, by screws driven upward through the base and into laterally-projecting lugs 4.

50 5 is the circuit-closing bar, which is arranged inside the housing and is vertically guided

by means of flanges 6 or other means suitable for this purpose. Said circuit-closing bar carries upon its ends contacts 7, which are adapted to co-operate with the terminals to establish 55 the circuit. They may be of any usual or approved form. As will be observed by reference to Fig. 1, the circuit-closing bar is open at its central portion, and at either side of the housing it carries a pair of uprights 8, which 60 are firmly secured to said bar or are formed integral therewith.

9 are pins passed through the tops of each pair of uprights, and to each pin is pivoted a depending lever 10, whose lower end is preferably provided with a roller 11. Between each of the levers 10 and the end wall of the opening in the circuit-closing bar is interposed a spring 12, so compressed as to exert a constant pressure in the direction of its length. 70 Said springs are retained as against displacement by any simple device—such, for instance, as the pins 13 shown at Figs. 3 and 4.

14 is the operating-handle, provided with a knob 15 and guided in ways in the top and bottom of the housing, the base being recessed beneath the end of said handle, as shown at 75 16. The handle is preferably provided with some means to prevent it from turning—as, for instance, groove 17—in which may run any 80 suitable pin projecting from the housing. Secured upon each side of the handle 14 is a double-faced cam 18, and above and below said cam are recesses 19, in which the rolls 11 may rest; but these recesses are not essential. 85

In the operation of the switch just described the make and break movements of the circuit-closing bar are effected by a longitudinal movement of the handle 14. Referring now to Fig. 3, when it is desired to open the circuit the handle is pushed downwardly. This drives the cams 18 in between the rolls upon the levers 10, thereby compressing the springs 12 until such time as the highest portions of the cams have passed the rollers, when the 90 springs acting upon the descending portions of the cams will throw the bar upward with a quick sharp movement, the parts being then in the position shown at Fig. 4. When in a state of rest either at the open or closed position, the rolls upon the levers rest within the recesses 19. When the switch is closed, press-

ure of the springs is constantly exerted to retain the bar in firm contact with the terminals, as will be seen by the slightly-inclined position of the springs in Fig. 3.

- 5 I do not wish to be confined to the precise arrangement and mode of interaction of the several parts as herein shown and described, since these may be varied without departing from the essentials of my invention.
- 10 In connection with this application I desire to refer to a certain other application for similar subject-matter filed by me January 26, 1891, No. 379,002, which is in some respects analogous to the devices herein shown
- 15 and described.

Without limiting myself to the precise details of construction, I claim—

1. In an electric switch, the combination, with the circuit-terminals, of a movable and
20 suitably-guided circuit-closing bar, a spring contained within said bar and compressible and expansible in the line of the length of the same, an operating - handle bearing a double-faced cam, and a swinging lever inter-
25 posed between the cam-face and the spring, substantially as described.

2. In an electric switch, the combination, with the circuit-terminals, of the movable and suitably-guided circuit-closing bar, a pair of springs contained within said bar and com- 30 pressible and expansible in the line of the length of the latter, an operating-handle carrying double-faced cams, and a pair of swing- ing levers interposed between the cam-faces and the springs, substantially as described. 35

3. In an electric switch, the combination, with the circuit-terminals, of the movable and suitably-guided circuit-closing bar, two pairs of uprights carried by said bar, a lever ful- crumed between and depending from each 40 pair of uprights, compressible springs inter- posed between said levers and the end walls of the bar, and an operating-handle provided with double-faced cams mounted and adapted to move between the levers and at right an- 45 gles to the bar, substantially as described.

In testimony whereof I affix my signature in presence of two witnesses.

HORACE T. CLARK.
